UNITED STATES PATENT OFFICE.

NESSING J. MATTHEWS, OF LAKewood, OHIO.

COVER FOR SHOES OF SHOE SKATES.

Application filed February 17, 1926. Serial No. 88,786.

This invention, as indicated, relates to a cover for the shoe of a shoe-skate. More particularly it comprises an elastic member having waterproof characteristics which 5 may be securely fitted over the shoe of a shoe-skate after the shoe-skate has been placed upon the foot of the wearer.

The use of shoe-skates particularly in the large centers of population is practically 10 universal and while in some instances the shoes are constructed of heavy waterproof material, in many instances they are of light leather and are not in any sense waterproof. This oftentimes adversely affects the skater's 15 health for the reason that in skating over the ice where pools of water and wet snow are encountered in spots, the skater's feet become saturated with moisture.

With clamp skates, and particularly 20 skates of the type formerly used by women having a heel socket and strap at the rear end and a strap or clamps at the forward end, the skate was often applied over the ordinary rubber shoe. Such expedients, 25 however, are impossible with the shoe-skate and they were not generally in use with detachable skates for the reason that rubber shoes of the ordinary type are extremely cumbersome and the weight thereof would 30 soon be noticed by a skater.

Through the present invention the disadvantages above mentioned are obviated and 35 every skater may be supplied with a means for keeping the shoes dry irrespective of the amount of snow and water which may be 40 encountered upon the surface of the ice.

To the accomplishment of the foregoing and related ends, said invention, then consists of the means hereinafter fully 45 described and particularly pointed out in the claims.

The annexed drawing and the following description set forth in detail certain structure embodying the invention, such disclosed 50 means constituting, however, but one of various structural forms in which the principle of the invention may be used.

In said annexed drawing:—

Fig. 1 is a side elevation showing a shoe-skate with the cover applied to the shoe thereof; Fig. 2 is a bottom plan view of the device shown in Fig. 1; Fig. 3 is an enlarged detail view showing the bottom of the toe portion of the cover; Fig. 4 is an 55 enlarged detail view showing the bottom of the heel portion of the cover and indicating

the strap and buckle of the shoe; and Fig. 5 is an enlarged sectional view taken along the line 5—5 shown in Fig. 1, looking in the direction of the arrows. 60

As is clearly shown in Fig. 1 of the drawing, a shoe 1 having a permanently attached skate 2 is adapted to be engaged over substantially its entire upper portion or "upper" by means of a cover 3 which conforms 65 to the shape of the shoe. The cover is preferably made of pure gum rubber in the form of a tapered sleeve and similar in outline to the shape of the foot. The cover thus has a high degree of elasticity and may 70 be stretched to the necessary extent to pass it over the foot and up the leg towards the knee while the shoe-skate is being applied. After the skate is laced up, the cover is 75 drawn down into position. Where a short skate is used, the cover may be stretched to the necessary extent to pass it over the skate proper as well as the shoe. The tension is then relaxed and the cover adjusted to proper position, conforming to the configuration of the shoe. The upper edge of the cover may be finished with a bead to prevent 80 accidental tearing.

As is clearly shown in Figs. 2 and 5, the cover is provided with a narrow marginal 85 sole portion 4 which preferably is of somewhat heavier gauge than the body portion thereof. The cover, as has been stated, is preferably made of a pure gum rubber which has a high degree of elasticity and is 90 of extremely light weight; thus none of the disadvantages are met with as would result if an attempt were made to cover the shoe with a molded rubber protector somewhat akin to the rubber shoes used by pedestrians. 95

The method of manufacture would preferably be by a dipping process and the elasticity provided in the body portion of the device would be such that a single cover would accommodate itself to a variety of 100 shoes. However, while the assortment of sizes may not need to be as extensive as with ordinary footwear, some approximation as to the size of the foot, of course, is required.

As is clearly shown in Fig. 5 of the drawing, the sole portion of the cover is thickened and is provided with a thickened lower side portion 5 adjacent thereto. The sole 6 of the shoe is thus firmly engaged at its marginal portions by the thickened walls of 110 the lower portion of the cover.

The sole portion adjacent the instep is

extended into a wide flange 7 so as to effectively prevent the entrance of moisture or wet snow at such point. At the toe of the skate the marginal portion is provided with 5 a cut out 8 to allow for the free passage of the toe support 9. A cut out 11 adjacent the heel of the skate may be provided to accommodate the strap buckle 12 which is frequently supplied on the bottom of the shoe 10 at such point. The strap 13 is preferably placed around the instep of the wearer on the outside of the cover. In many instances, however, the strap is dispensed with, the shoe itself embodying reinforcing members 15 to support the ankle.

Other modes of applying the principle of my invention may be employed instead of the one explained, change being made as regards the structure herein disclosed, provided the means stated by any of the following claims or the equivalent of such stated means be employed.

I therefore particularly point out and distinctly claim as my invention:

25. 1. An article of the character described, having in combination a highly elastic body portion of waterproof characteristics adapted to be engaged over the shoe of a shoe-skate, and a marginal portion of greater thickness adapted to engage and underlie the marginal portion of the sole of said shoe.

30. 2. An article of the character described, having in combination a highly elastic body portion of waterproof characteristics adapted to be engaged over the shoe of a shoe-

skate, and a marginal portion of greater thickness adapted to engage and underlie the marginal portion of said shoe, said marginal portion having a widened area adjacent the instep to prevent the entrance of moisture. 40

3. An article of the character described, having in combination a highly elastic body portion of waterproof characteristics adapted to be engaged over the shoe of a shoe-skate, and a marginal portion of greater thickness adapted to engage and underlie the marginal portion of the sole of said shoe and having a cut-out portion adjacent the toe to accommodate the toe support of the shoe-skate. 45

4. An article of the character described, having in combination a highly elastic body portion of waterproof characteristics adapted to be engaged over the shoe of a shoe-skate, and a marginal portion of greater thickness adapted to engage and underlie the marginal portion of the sole of said shoe and having a cut-out portion adjacent the heel to accommodate the strap buckle of a shoe-skate. 50

5. A cover for the shoe of a shoe-skate, comprising a thin tapered sleeve of pure gum rubber, adapted to be engaged over a portion of the upper of the shoe, and means adjacent the lower edge thereof to hold said cover in position. 55

Signed by me this 13th day of February, 1926.

NESSING J. MATTHEWS.
